United States Patent Office

Des. 177,044
Patented Mar. 6, 1956

177,044

PASTE DISPENSER

Weddie Howard Hassler, Memphis, Tenn., and Raymond W. Barton, Evansville, Ind., assignors to Mead Johnson & Company, a corporation of Indiana

Application November 29, 1954, Serial No. 33,290

Term of patent 14 years

(Cl. D83—1)

We claim:

The ornamental design for a paste dispenser, as shown.
